DESIGN FOR A COMBINATION MOTION PICTURE SCREEN AND CARRYING CASE

Abraham Shapiro, Chicago, Ill., assignor to
Ampro Corporation, Chicago, Ill., a corpora-
tion of Illinois

Application November 4, 1942, Serial No. 108,696

Term of patent 7 years

To all whom it may concern:

Be it known that I, Abraham Shapiro, a citizen of the United States, residing at 2832 Ainsley Avenue, in the city of Chicago, county of Cook, and State of Illinois, have invented a new, original, and ornamental Design for a Combination Motion Picture Screen and Carrying Case, of which the following is a specification, reference being had to the accompanying drawing, forming part thereof.

Fig. 1 is a plan view in closed position of the combination motion picture screen and carrying case showing my new design.

Fig. 2 is a perspective view of the case closed taken from the rear.

Fig. 3 is a front perspective view of the case in open position for use.

Fig. 4 is a plan view of the parts in the positions shown in Fig. 3.

I claim:

The ornamental design for a combination motion picture screen and carrying case, as shown.

ABRAHAM SHAPIRO.
